UNITED STATES PATENT OFFICE.

EDWARD HARRISON McCLOUD, OF COLUMBUS, OHIO.

FLEXIBLE FIRE-RESISTING CURTAIN.

No. 910,218.

Specification of Letters Patent.

Patented Jan. 19, 1909.

Application filed February 9, 1905, Serial No. 244,992. Renewed January 7, 1907. Serial No. 351,226.

To all whom it may concern:

Be it known that I, EDWARD HARRISON McCLOUD, a citizen of the United States, residing at 209 South Monroe avenue, Columbus, county of Franklin, and State of Ohio, have invented new and useful Improvements in Flexible Fire-Resisting Curtains; and I do hereby declare the following to be a full, clear, and exact description of the invention, 10 such as will enable others skilled in the art to which it appertains to make and use the same.

This invention relates more particularly to a tubular slat adapted to contain a heat-retarding material, an instance of which is seen in the United States patent of W. R. Kinnear No. 546,858, dated September 24, 1895, and the object of the present invention is to make an improvement upon this form 20 of slat generally.

It is manifest that when a curtain constructed of slats of tubular form having their opposite sides formed of separate strips of metal is subjected to the heat of fire at 25 one side, the sides of the slats exposed to greater heat expand at a greater rate.

The particular purpose of this invention, therefore, is to provide means whereby the metal sides of the slat are held together but 30 are permitted to move longitudinally one upon the other, when subjected to great heat, as from a near-by fire.

In the accompanying drawing—Figure 1 is a perspective view of a portion of a curtain containing my present improvement, one of the washers being removed; Fig. 2 is a 35 horizontal section on the line $x-x$ Fig. 1.

In said views a^1 designates the heat-retarding medium, which is incased between two 40 metallic side pieces or strips a^2 and a^3 that are secured together but so as to be capable of sliding longitudinally with reference to each other when subjected to great heat.

In the particular instance of slat here 45 shown the side a^2 is formed on a reverse curve a^4 that terminates in an open ellipse. The lower edge of the side a^3 is formed semi-circular and terminates in an inward bend, as seen at a^5 . The curved portion a^4 and the 50 bend a^5 of adjoining slats form a hinge joint permitting the curtain to be flexed and rolled up upon a roller. But in practicing my present invention I do not confine myself to the use of the particular joint for the slats 55 just described, as any other suitable form of

joint may be adopted. The particular form of joint which I have just described is disclosed in my patent of the United States No. 806,174, dated December 5, 1905.

As before indicated, a curtain of this character will ordinarily have but one side exposed to the action of fire and the metallic side pieces of the slats exposed to the fire will expand to a greater extent than those not so exposed, especially when the intervening heat-retarding medium a^1 is interposed between the sides. This difference in the expansion of the two sides of the slat will often cause the slat to buckle or bulge and depart from its original form. Indeed, 60 they may sometimes come open at the edges where the joint is formed. To prevent this I connect the opposite metallic sides of the slat by means of a bolt or rivet, as at a^6 , having one end securely fixed in one of the 65 pieces or strips, as a^2 , and the other end extending through a slot a^7 extending longitudinally of the slat, as a^8 . The end of the rivet in the slat a^3 is headed on a metallic washer a^9 covering the slot; but with the 70 said riveted head of larger diameter than the slot the washer can be omitted.

While it is better to secure the rivet at one end and in one of the slats, with its other end projecting through a slot in the other slat, I 75 do not confine myself to this particular construction.

What I claim and desire to secure by Letters Patent is:

1. A flexible curtain constructed mainly of a plurality of slats or sections hinged together each slat or section composed of two metallic sides, a heat-retarding medium between said sides, and means securing said sides together but permitting them to slide longitudinally with reference to each other.

2. A flexible fire-resisting curtain composed mainly of interlocking slats, each of said slats having a heat-resisting medium, two metallic sides inclosing said heat-resisting medium, one of said sides provided with a longitudinally extending slot and a headed securing device to engage the outer sides of said slats and having its shank passed through said slot and fixedly connected to the opposite side to hold said slats together, but permit them to expand longitudinally independently of each other.

3. A flexible fire resisting curtain composed mainly of interlocking slats, each slat

- having a heat-resisting medium, two metallic sides inclosing said heat-resisting medium, one of said sides provided with a longitudinally extending slot, a headed securing device extending through said slot and fixedly secured to the opposite side, and a washer-like piece between the head of said securing device and the slot of the slotted side to cover said slot.
- 10 4. A slat for the construction of flexible curtains constructed of two strips or sides of sheet metal and with means at the edges of said slat for hingedly connecting it to other slats, a heat-retarding medium interposed between said strips or sides, and means tying said sides together but permit-
- 15

ting said sides to expand longitudinally independently of each other.

5. A slat for the construction of flexible curtains constructed of two strips or sides of sheet metal and with means at the edges of said slat for hingedly connecting it to other slats, and means tying said sides together but permitting said sides to expand longitudinally independently of each other. 25

In testimony thereof I affix my signature in presence of two witnesses.

EDWARD HARRISON McCLOUD.
